HEAT EXCHANGE APPARATUS

Filed Nov. 5, 1929

UNITED STATES PATENT OFFICE

NORMAN H. GAY, OF LOS ANGELES, CALIFORNIA

HEAT-EXCHANGE APPARATUS

Application filed November 5, 1929. Serial No. 404,939.

This invention relates to improvements in heat exchange devices, and more particularly concerns a structure which is adapted for the cooling of liquids.

One of the objects of the present invention is to provide a heat exchange skeleton which is formed of relatively simple and easily constructed members and which in assembly provides a rigid whole.

Another object of the present invention is to provide means whereby the incoming warm liquid itself produces a circulation and agitation of the liquid being cooled, and promotes the effective contact of such liquid with the cooling members.

These and other objects will appear in the course of the following specification and claims, in conjunction with an illustrative exemplification of the invention set forth in the accompanying drawings, in which:

Fig. 1 is a vertical sectional view, substantially on line 1—1 of Fig. 2.

Fig. 2 is a horizontal sectional view, substantially on line 2—2 of Fig. 1.

The heat exchange or cooling device according to the present invention is intended particularly for the cooling of water, brine and other liquids, although obviously not limited solely to such employments. It com-

prises an external receptacle to receive the liquid to be cooled, an internal skeleton comprising headers and pipes for receiving the cooling medium, and inlet means for the liquid to be cooled, comprising a delivery header provided with nozzles for directing the liquid in such manner that it causes a circulation and agitation within the receptacle.

In the drawings, the receptacle is illustrated as having a body 10 with closing upper and lower domes 11 and 12. The upper dome or cover receives a gas withdrawal pipe 13 having a supporting and liquid-tight connection 14. Within the receptacle are located the inlet header 15 and outlet header 16, which are preferably located at right angles when four coils are employed, as will be set forth hereinafter, the inlet header being located near the bottom of the receptacle 10 and the outlet header near its top. Connect-

ing these two headers are a plurality of coils 17, 18, 19, 20, each of which has its lower end joined with the inlet header 15 and its upper end joined with the outlet header 16. It will be noted that the coils 18 and 20 are substantially identical, while the coils 17 and 19 are symmetrical thereto. In this way, a very simple, symmetrical and compact arrangement is provided, so that the weight of the entire structure may be supported from the upper dome 12.

A liquid refrigerant inlet pipe 21 likewise passes through a sealed joint in the cover 12 and is in communication at its lower end with the interior of the inlet header 15. It is provided externally of the receptacle with a control valve 22. Also, an oil purging pipe 23 passes in sealed condition through the cover 12 and enters the inlet header 15 and opens adjacent the bottom thereof: it likewise is provided with a control or purging valve 24.

The inlet pipe 25 for the liquid to be cooled passes through the side wall of the jacket 10 of the receptacle, being provided with an inlet control valve 26 and having a tight supporting joint connection 27 at the wall 10. This pipe extends inwardly to a point adjacent the axis of the container jacket 10 and is there in communication with a vertical hollow column 28 which is located centrally of the four cooling coils 17, 18, 19 and 20 (Fig. 2). In Fig. 1, the hollow column 28 is indicated as joined to the inlet header 15 and outlet header 16 by straps 33, 34 which are welded in position, and serves to unite the structure into a coherent whole which may be handled as a unit without fear of rupture or distortion; and facilitating the suspension of all parts of the apparatus from the cover 12.

This hollow column 28 is provided with a number of nozzles or nipples 29 located with their axes in a single vertical axial plane of the column in the illustrated form.

An outlet pipe 30 for the cooling liquid is provided near the bottom of the receptacle, likewise having a sealed joint 31 and a valve 32.

In operation, liquid is permitted to enter from the pipe 25 past the valve 26 so that it flows into the hollow column 28, and can

escape therefrom only through the nozzles 29 in jets. As the liquid collects in the receptacle 10, the delivery occurs through more and more of the jets according to the flow and pressure of the liquid as well as the liquid level in the receptacle 10. It will be understood, however, that the normal condition of the device is with the receptacle substantially full of liquid being cooled.

10 The valve 22 is now opened and liquid refrigerant of any known type is permitted to enter the lower or inlet header 15. This refrigerant flows upward in the several coils 17, 18, 19 and 20, and by evaporation therein is converted to a gas which escapes from the outlet header 16 through the gas return pipe 13 for recompression and reliquefaction in the usual manner and returned to the pipe 21. The level of liquid refrigerant in the coils and therewith the rate of cooling may be regulated by the valve 22.

15 As liquid is drawn off from pipe 30 through valve 32, further liquid enters through pipe 25, and escapes through the nozzles 29 in the form of jets directed substantially tangentially between the pairs of coils 17-20 and 18-19 as indicated by arrows in Fig. 2, whereby an active circulation is established of the liquid through and around the coils, thus promoting a thorough agitation or mixing of the liquid within the receptacle 10, and a substantially uniform cooling thereof. When oil accumulates within the inlet header to such an extent that it obstructs the efficient evaporation, it may be drawn off by opening the purging valve 24 in the usual way.

20 It will particularly be noted that the assemblage of headers and coils is supported from the top cover by means of the inlet and outlet pipes for refrigerant and the purging pipe: so that a very compact and yet strong and rigid mounting is provided.

25 It is obvious that the structure may be modified in many ways from the illustrated example, without departing from the scope of the invention.

Having fully described my invention what I claim as new and desire to secure by Letters Patent is:—

30 1. In a heat exchange apparatus, a receptacle, inlet and outlet headers located at right angles to one another and spaced apart in a vertical direction, a plurality of coils connecting said headers, means to admit refrigerant to the inlet header and to withdraw gaseous refrigerant from the outlet header, and a substantially vertical hollow column for the liquid to be cooled, said column being provided with a plurality of apertures to produce jets of liquid whereby to cause mixing of the liquid within the receptacle.

35 2. In a heat exchange apparatus, a lower inlet header, an upper outlet header, vertical planes passing through said headers intersecting in a vertical line, the ends of each of

said headers being located substantially equal distances from said line, four cooling coils connected at their lower ends into said inlet header and at their upper ends into said outlet header, a liquid refrigerant inlet pipe extending downward and in communication at its lower end with said inlet header, a gaseous refrigerant return pipe in communication with said outlet header, and means connected to said pipes to support the assembly. 70

3. An apparatus as in claim 2 in which the assembly is enclosed within a receptacle, and the cover of the receptacle provides the means for supporting said pipes. 75

4. An apparatus as in claim 2 in which a hollow column is located with its axis substantially coinciding with said vertical line, and means for delivering liquid is in communication with said hollow column, said hollow column being provided with apertures for the passage of the liquid to be cooled so that the jets of liquid from said apertures pass substantially tangentially between pairs of said coils. 80

5. In a heat exchange apparatus, a receptacle adapted to contain the fluid to be treated, inlet and outlet headers and means whereby the heat exchanging fluid is delivered to and removed from the same, a pair of spaced coils connected between said headers, and an inlet member for the fluid to be treated extending opposite the space between the coils, said member having means to produce a rapid jet-like flow of fluid from said member into the receptacle whereby to cause a circulation of the fluid within the receptacle between and through the coils and over the surfaces. 90

6. In a heat exchange apparatus, a receptacle adapted to contain the fluid to be treated, inlet and outlet headers and means whereby the heat exchanging fluid is delivered to and removed from the same, spaced coils connected between said headers, and an inlet member for the fluid to be treated located in the space between the coils, said member having means to produce a rapid jet-like flow of fluid from said member into the receptacle whereby to cause a circulation of the fluid within the receptacle between and through the coils and over the surfaces. 105

7. In a heat exchange apparatus, a receptacle adapted to contain the fluid to be treated, inlet and outlet headers and conduits whereby the heat exchanging fluid is delivered to and removed from the same, spaced coils connected between said headers, an inlet member for the fluid to be treated having rigid mechanical connections to said headers, and means to support the assembly of headers and inlet member in said receptacle, said member having means to produce a rapid jet-like flow of fluid from said member into the receptacle whereby to cause a circulation 110

of the fluid within the receptacle between and through the coils and over the surfaces.

8. A heat exchange apparatus as in claim 7, in which the receptacle has a cover and the assembly is suspended from the cover.

5 9. A heat exchange apparatus as in claim 7, in which the receptacle has a cover, and at least one of the conduits extends through and is mechanically connected to the cover whereby to support said assembly.

10 10. In a heat exchange apparatus, a receptacle adapted to contain the fluid to be treated, spaced inlet and outlet headers and means whereby the heat exchanging fluid is delivered to and removed from the same, a plurality of conduits connecting said headers, and a hollow supply member located between said headers and provided with a plurality of apertures to produce jets of entering fluid 15 whereby to cause the entering fluid and the fluid present in the receptacle to become agitated and mixed to pass over the surfaces of said conduits.

20 In testimony whereof, I affix my signature.
